(57) **CLAIM**

The ornamental design for a packaging container lid, as shown and described.

DESCRIPTION

FIG. 1 is a front view of a packaging container lid according to my new design;

FIG. 2 is the right view thereof;

FIG. 3 is the top view thereof;

FIG. 4 is the bottom view thereof;

FIG. 5 is the cross-sectional view thereof along the line 5-5 in FIG. 2; and,

FIG. 6 is the perspective view thereof.

The features of the packaging container lid shown in broken lines form no part of the claimed design.

1 Claim, 6 Drawing Sheets
